TRAFFIC CONTROL SYSTEM

Alfred Percy Bailey Renshaw, Kingston Hill,
England, assignor, by mesne assignments, to
Automatic Telephone & Electric Company,
Limited, London, England

Application January 19, 1935, Serial No. 2,480
In Great Britain February 5, 1934

18 Claims. (Cl. 177—337)

The present invention relates to traffic control systems for use at the intersection of interfering traffic lanes and is more particularly concerned with a progressive type traffic control system by means of which a number of controllers located at adjacent intersections on a main road may be regulated from a master controller in a definite phase relationship to another. In known forms of progressive systems it has been found that for efficient working the value of the cycle time requires alteration a number of times each day to cater for different conditions of traffic, and various methods have been employed to overcome this difficulty such as manually or clock-controlled cycle adjustment.

The principal object of the present invention generally stated is to provide an improved progressive traffic control system in which the cycle time is variable automatically in accordance with the traffic conditions existing at any particular time.

More specifically, one object of the invention is to provide a traffic control system for a plurality of intersections in which the right of way signal controllers at the several intersections are operated on a cycle of variable length depending upon the cycle length of a controller at one intersection which is selected as having typical traffic conditions, and which is equipped with vehicle detectors in the several lanes of approach thereto.

In applying the principles of the invention the area to be controlled is first surveyed as regards its traffic conditions to locate what will be known as the key intersections, that is, in effect sample intersections or intersections at which the conditions may be considered as typical of those existing at the intersections in the immediate vicinity. When the key intersections have been selected, the remaining intersections to be controlled are shared out between them with the result that the area is split up into a number of groups, each containing a key intersection and half a dozen or so dependent intersections which are assumed to have similar traffic conditions and are controlled from the key intersection of the group. In each group the key intersection is provided with a "key controller" and a master timer, construction of which will subsequently appear, and vehicle actuatable devices, or detectors, in each of its several lanes of approach. The dependent intersections of each group are equipped with controllers which may be regulated from the master timer of that group in a desired phase relationship with one another, and which may be called dependent controllers.

In one aspect of the invention the arrangement for adjusting the time cycle of the master timer by the key controller to more nearly conform to the cycle of the latter has general application in the field of synchronizing a secondary timer with a primary timer and application of the invention in this field forms the subject of copending divisional application Serial No. 140,873.

In applying the invention to a traffic control system the controller at the key intersection, which is fully vehicle-actuated, is arranged to co-operate with the master timer so that if the key controller or primary timer operates on a shorter cycle than the master or secondary timer an adjustment will automatically be made at the end of the master timer cycle so that its following cycle will be shorter. If on the other hand the master timer finishes its cycle first, an adjustment will be made to increase the length of its following cycle. In each case the adjustment will not be sufficient to correct the master timer cycle completely unless the discrepancy is very small otherwise the cycle would vary as at a fully vehicle-actuated intersection and a progressive flexible system would be impossible. Small adjustments therefore, only are made and the master timer cycle value becomes an average of the cycle time of the key controller. If the key controller finishes its cycle before the master timer, it waits until the master timer has finished its cycle, and it is clearly desirable that the controller shall be connected so that at the end of the cycle right of way is with the main road. If the key controller finishes its cycle after the master timer after possibly some degree of curtailment, it will immediately start its next cycle, but the master timer itself does not stop under any conditions. By this means the dependent controllers can be linked to form a progressive system which is governed by a cycle time varying on the average with that at the key point.

Several variations of the principle are possible, for instance, the dependent controllers may have detectors in the side road only, as suggested above, or no detectors at all and simply a varying cycle time, or detectors may be provided in all roads with freedom for right of way to be given to either road except under heavy traffic conditions, when the right of way periods will come under the control of the master timer. It is also possible within a particular group to employ different types of dependent controllers so as to form a combination of two or more of the three types described.

The invention will be better understood from the following description of one method of carrying it into effect which may advantageously utilize arrangements disclosed in British specification 403,732, from which specification portions describing these arrangements are reproduced herein. Application Serial Number 677,029, filed June 22, 1933 under the international convention, corresponds with British specification 403,732 and is now co-pending with the present application. No claim is made in the present application to subject matter common to the present application and the co-pending application, such subject matter being claimed in the co-pending application.

The description will be made clearer with reference to the accompanying drawings which illustrate one practical embodiment of the invention, and in which:

20 Figure 1 illustrates a master timer from which separate pairs of conductors radiate to dependent controllers.

25 Figure 2 illustrates one type of controller for a dependent intersection, regulated by impulses transmitted from the master timer.

30 Figure 3 is a wiring diagram for a type of right of way controller whose operation is dependent upon actuation of vehicle actuatable detectors in the several approaches to the intersection and upon pulsing from the master timer.

35 Figure 4 shows the modifications required in a right of way controller of the type shown in Figure 3, according to the present invention, for rendering such a controller suitable for use at a key intersection, and connections to the master timer operating in conjunction therewith.

40 Figures 5 and 6 are each sectional views of a conventional differential gearing arrangement, utilized in a rotary stepping switch with dual stepping magnet and ratchet apparatus for producing movement of the wiper arms either clockwise or counterclockwise for use in the master timer.

45 Figure 7 shows a modification of Figure 3 providing for master timer control impulses twice per cycle.

The system described in specification #403,732 relates to traffic control signals for use at road crossings or the like and is more particularly concerned with a progressive type traffic control system by means of which a number of controllers located at successive intersections at a main road may be regulated from a master controller in a certain phase relationship to each other, so that 50 if the average speed of the traffic is known it is possible to time the control signals so as to ensure a substantially continuous flow of traffic along the main road. The arrangement moreover is particularly concerned with systems in which the operation of the signals may be controlled in accordance with the density of the traffic by the employment of vehicle detectors located in the roadway.

60 The system shown in Figs. 1 and 2 does not make use of vehicle detectors to regulate the timing of the signals but its operation will be described in order to permit a proper understanding of the system illustrated in Fig. 3 in which vehicle detectors are employed.

70 It should be explained generally that the system illustrated in Figs. 1 and 2 comprises a master timer, from which separate pairs of conductors radiate to each controller for the purpose of regulating their time periods in relation to 75 each other. The controllers in one embodiment

may be conveniently arranged to operate at fixed time periods independent of the traffic flow, that is to say, there is no question of extending their normal period as a result of a continuous flow of traffic passing over a road contact or the like. 5 These controllers will be set to operate at rather long periods, considerably in excess of that required in the progressive system, but the periods will be curtailed by the right amount upon the reception of so-called "light" and "heavy" pulses 10 over the control leads from the master timer.

Referring now to the circuit shown, the system is arranged for operation from A. C. mains and suitable rectifying arrangements are provided for obtaining direct current to operate the 15 relays and neon lamps. In the drawings the alternating current mains designated 10 and 11 are shown incoming from the left hand side in Fig. 1 and for the operation of the master timer a tapping is made from these leads by way of the 20 fuses FUS and main switches MNS to the primary winding of the transformer XFR. This transformer is provided with three secondary windings two of which connect with the thermionic valve amplifier VLV which supplies direct 25 current of the order of 400 volts to the terminals designated + and - in a circle, for the purpose of flashing the neon lamp N. The third winding on the secondary side of the transformer XFR connects with the full wave metal rectifier bridge 30 MRA which supplies direct current of the order of 50 volts to the terminal points marked + and - in a square, for the purpose of operating the relay F and the driving magnet DSM. Essentially the master timer comprises a rotary step- 35 by-step switch DST of the type used in automatic telephone systems which is completely immersed in oil and arranged to be operated step by step from a neon lamp impulser, the speed of which may be altered, by varying the setting 40 of the resistance switch 12 connected in series with the condenser QB.

As regards the automatic stepping circuit it should be explained that when the neon lamp N flashes as the result of the charging of the 45 condenser QB to the required voltage, relay Z is operated in series therewith, thereby at armature z1 operating relay F, and at armature z2 connecting negative potential to the wipers of the switch DST. Relay F on operating, at armature 50 f1 completes the circuit for the driving magnet DSM, at armature f1 supplements the connection to the wipers of the switch DST, at armature f3 shunts the neon lamp N and relay Z as also condenser QB, by way of resistance YB and at armature f4 flashes the master fail alarm lamp MFA. Relay Z thereupon releases and upon the release of relay F after its slow period due to the copper slug on its core, the driving magnet is de-energized to advance the wipers on to the 60 next set of bank contacts. This action continues automatically so long as the system is in service. One bank and wiper of the switch DST is allotted to each controller to be regulated and the control leads extend from the appropriate contacts in the 65 associated bank. Bank 1a connects with controller No. 1 of which only the regulating relays have been shown in the dotted rectangle; this controller may be located adjacent to the master timer. Bank 2a connects with controller No. 2 70 shown in Fig. 2, and bank 3a connects with controller No. 3, which is not shown as it is assumed to be identical with controller No. 2.

In the drawing each control lead is shown as making two connections with its associated bank, 75

one of which is direct and the other extends by way of a resistance. Consequently as the switch rotates so-called light and heavy pulses are delivered over the control leads to the respective controllers in turn.

5 The control leads may comprise light gauge wires, for example telephone lines, and terminate in the controllers on a pair of relays B and C shown in Fig. 2 connected in series, one of which 10 is marginal. As a result of the operation of one or both of these relays from the light and heavy pulses the signal lights of the controller are regulated accordingly.

In this particular example the complete cycle 15 time of the system is represented by 25 steps of the rotary switch DST in the master timer. Each step of the switch therefore represents 4% of the total cycle time so that by varying the connection of the control leads to the banks the 20 phase relationship between the different sets of control signals may be adjusted to a very fine degree.

Each of the controllers, which are all identical, 25 comprises essentially a battery of cams mounted on a common shaft and arranged to close contact springs in a particular order. As regards the No. 2 controller shown in Fig. 2 it should be explained that the cam shaft is rotated step by step under the control of a solenoid S 30 which is impelled at predetermined time periods from a neon lamp timing device, comprising the lamp LN and impulse relay A together with condenser QA and charging resistance 13. The cam assembly is moreover, a standard unit which 35 may be used in different circumstances and controls 22 spring sets with six different positions. The full number of cams is not employed in the present instance and the chart shown in Fig. 2 shows the effect of the various cams which are 40 used in this particular arrangement. The cam contacts which are operated in each of the six positions are designated in the chart by a black circle or bar.

If it is assumed with regard to controller No. 45 2 that the cam shaft is in its first position, cam contacts C1, C9 and C22 will be operated, thereby lighting the green signals lamps GNS for the north-south road, and the red signal lamps REW for the east-west road, while at the same time 50 over cam contacts C1, a circuit is complete from the valve rectifier IVLV by way of a tapping on the common resistance 13 for charging the condenser QA. After the initial period of for example 10 seconds has elapsed, the condenser QA 55 will be charged sufficiently to cause the neon lamp IN to flash over, thereby operating relay A which at armature a1 energizes the solenoid S which advances the cam shaft into its second position. In this position, as will be evident from 60 the chart, the signal lamps already lit are maintained and over cam springs C2 and the adjusting switch shown a charging circuit is again completed for the condenser. Four such adjusting switches are shown in the drawings and 65 it should be explained that the terminals of these switches connect with suitable tapping points on the common resistance 13. To meet the requirements of the invention the resistance now connected in circuit must be very high to ensure 70 that the condenser charges slowly, and for this reason the adjusting switch in question is preferably turned round into its extreme position where it will be understood that it connects with the end of the common resistance shown.

75 During progressive working this particular

timing circuit will have practically no effect on the operation of the controller since with the normal operation of the master timer a light pulse is delivered over the control leads before it becomes operative to charge sufficiently condenser QA. As already explained this light pulse is obtained by including a high resistance in the pulse leads at the banks of the master timer, and as a result relay B only is operated in the controller, thereupon at its armature b1 in conjunction with the cam contacts C18 completing a low resistance charging circuit for the condenser QA. Almost immediately therefore the neon lamp IN 5 flashes and causes the controller to step to position 3. Non-inductive resistances are connected 10 across the control leads as shown in order to guard against false operation owing to surges and inductive discharges.

In accordance with the change of the cam contacts, the green lights for the north-south 20 road are now replaced with amber lights ANS, and over cam contacts C3 and the adjustable resistance switch a circuit is completed for the condenser QA to control the duration of the amber signal. With this arrangement although the 25 phase of the amber signal may be changed when an adjustment is made in the cycle at the master timer, its actual duration remains constant since it is determined by the setting of the local adjusting switches and is not influenced by the 30 relays connected to the control leads.

In case it should be desired to show the amber signal simultaneously to both roads, as is the requirement of certain administrations, this may be achieved by bridging the amber circuits by 35 means of the switch 14 shown in the drawings. After the duration of the amber warning period the solenoid S again operates to step the cam shaft to position 4 and the control signals are then completely reversed while over cam springs 40 C4 a charging circuit is completed for the condenser QA which provides an initial timing period of 10 seconds for the east-west road. When this period has elapsed, the solenoid S steps the cam shaft to position 5 and although 45 the signals previously showing are retained, the charging circuit for the condenser QA is completed by way of the very high resistance as a result of the adjusting switch associated with cam contacts C5 being turned into an extreme 50 position.

Here again this second comparatively long time period has practically no effect upon the controller during normal progressive operation since a heavy pulse will be received from the 55 master timer meanwhile, which results in the operation of both relays B and C, and the latter at armature c1 in conjunction with the cam contacts C7 steps the cam shaft into its final position 6. In this manner the controllers are 60 stepped progressively depending on the connections to the banks of the timing switch, and providing the master timer is functioning correctly, the time periods of their "stop" and "go" signals will be directly regulated therefrom. 65

If however for any reason the master timer should fail in such a manner that no further impulses are delivered over the control leads, the individual controllers will continue to function satisfactorily at somewhat longer time intervals as a result of the charging circuits completed over the cam contacts C2 and C5. Moreover in case a particular line fault on the control conductors should maintain operated one or both of the signal relays at the controller, 70 75

the latter will continue to function at somewhat shorter time intervals as determined by the initial timing circuit completed over cam contacts C1 and C4.

- 5 In addition to the normal operation of the system and the necessary safeguard against failure, it is also possible to provide special features such as for example causing all controllers to show a red signal to all approaches thereby 10 effecting a compete hold up of the traffic. This condition may be brought about instantaneously from the master timer by the operation of the manual switch which closes the contact marked ARS in the drawings, thereby connecting potential to a common wire 15 extending to all controllers which results in the operation of a relay AR in each. Relay AR at armature ar1 disconnects the operating circuit for the controller which is thus brought to rest in the position 20 to which it is set, at armature ar2 opens the circuit of the green and amber signal lamps and at armature ar3 bridges the circuit of the red signal lamps so that both sets are lighted. It will be appreciated from a consideration of 25 the chart that in all positions of the controller one or other of the red signals will be showing and therefore, the connection described will be effective no matter in what position the controller is brought to rest.
- 30 For the purpose of switching the controllers on and off a further common wire 16 is provided which connects with the switch contact CSS3 at the master point and a relay CS in each controller. The operation of the manual 35 switch to a second position disconnects the master timer insofar as its control function is concerned by opening the circuit to the valve rectifier VLV at springs CSS1 and CSS2, and at springs CSS3 connects potential to the common 40 lead 16 to operate a relay CS in all controllers, which thereupon at armatures cs1 disconnect the respective controllers from the alternating current mains. This method of control is preferred to the alternative, whereby the relay is operated to connect up the controller since a failure 45 at the master timer might then result in the individual controllers becoming disconnected. In a further position of the manual switch springs CSS1 and CSS2 are opened but springs CSS3 are not closed. In these circumstances the master controller no longer sends pulses but the individual controllers are not switched off and 50 continue to operate independently.

Arrangements are also provided by means of 55 a special manual switch at each controller whereby the all red feature may be brought into action at that particular point only. When this manual key is operated, the springs ARS1 and ARS2 are actuated, thereby disconnecting the circuit 60 for the green and amber signal lamps and also connecting together the red signal lamps so that both sets show simultaneously regardless of the position of the controller.

In case it should become necessary under certain 65 circumstances for a particular controller to be operated manually, the required circuit changes are brought about by the operation of a further key which actuates the springs MAN1 and MAN2 to disconnect the timing circuit of the 70 controller and also connects the solenoid S in circuit with a push button PB. The operation of the push button by the officer in charge causes the controller to step through its cycle and any desired time periods may be allowed.

75 As already explained, a supervisory lamp MFA

is provided which is located in a conspicuous position at the master timer and arranged to flash in synchronism with the stepping switch. Any abnormal condition such as the blowing of the main fuse or failure of the neon lamp will 5 be indicated by the failure of the supervisory lamp to light.

In case the master timer is switched on at a time when certain of the controllers are out of phase, the correct phase setting between each 10 will be restored when the stepping switch in the master timer has made one complete revolution.

Considering now the arrangement of another embodiment of the controller illustrated in Figure 3, this represents the equipment at an individual controller which is intended to perform similar functions to that illustrated in Fig. 2. It will be appreciated however that the current supply arrangements are shown somewhat differently and also that relays such as CS, AR and C 15 will still be required to respond to signals from the master controller which in this case need send only one control impulse per cycle which operates relay C. The controller of Fig. 3 is of the same mechanical construction as that illustrated 20 in Fig. 2, that is to say, it is provided with a number of sets of contacts operated by a cam shaft which is moved step by step by means of a solenoid. Moreover, the stepping of the solenoid 25 is again controlled from a timing circuit employing a neon lamp condenser combination but in this case the timing is variable under the control of vehicle detectors located in the roadway. Moreover, two separate timing circuits are employed and two road relays are provided which 30 respond to the passage of vehicles over the detectors. In view of the description which has already been given it will not be necessary to describe in considerable detail the working of the apparatus illustrated in Fig. 3 but the more 35 salient features of operation will be considered briefly.

The current supply is assumed to be taken from alternating current mains and is rectified to provide direct current for the operation of the neon 45 lamps. The transformer XFR feeds the valve rectifier VR and also supplies alternating current of a suitably reduced voltage for the operation 50 of the road relays. The live pole of the A. C. circuits is represented by a plus in a circle, the live pole of the D. C. circuits by a plus in a square and the common earthed pole by a minus in a circle and a square. The chart shows as before the positions of the cam shaft in which the various cam contacts are closed. The various 55 interval adjusting switches INS, VNS, IEW, VEW, LNS, LEW are wired to appropriate tapping points of the resistance 20, and similarly the switches MNS and MEW are wired to resistance 21 which gives 60 tappings of higher value.

For convenience of description it will be assumed first of all that the cam shaft is standing in position 6 giving right of way to the street NS and that there is no traffic on either street. In these circumstances a charging circuit is completed over contacts C4 and the adjusting switch VNS for the condenser QJ, but owing to the fact that neither relay D nor relay E is operated in the absence of traffic assumed and the consequent absence of closure of road contacts DEW 70 and DNS, and with contact d2 therefore open, it is impossible for discharge to take place through the neon lamp FJ when the condenser becomes charged to the striking voltage since cam contacts C16 and C17 are open in this position 75.

tion. Moreover, while contacts $d2$ remain open, no charging circuit is completed at this time for the condenser QK and the tube FK and relay K cannot be operated even though the armature K cannot be operated even though the armature $c'1$ be operated due to the receipt of a pulse from the master timer, so that solenoid S cannot be operated and the cam shaft will remain in this position.

Suppose now that a vehicle arrives on the road EW , relay D will be energized due to the operation of a traffic detector DEW and since contacts $C6$ are closed, a circuit is completed over armature $d2$ for striking lamp FJ so that relay J is energized and the solenoid is operated at armature $j1$ and the cam shaft is moved to position 1. In this position the lamp ANS is lighted in place of GNS and lamp AEW is lighted in addition to lamp REW if the switch connection is used. Moreover, a new charging circuit is completed for condenser QJ over cam contacts $C13$, the adjusting switch LNS and the appropriate charging resistance. Relay D moreover was locked up over armature $d1$ and contacts $C1$ so that as soon as the condenser QJ has been charged sufficiently which will occur after a few seconds only, relay J is again operated and advances the cam shaft to position 2. In this position lamps GEW and RNS only are lighted and the vehicle in the street EW secures right of way. Furthermore a new charging circuit is now completed for condenser QJ , this time over contact $C14$ and switch IEW . Consequently, after the period corresponding to the resistance now included in the charging circuit, relay J is again operated and the solenoid steps the cam shaft to position 3. This produces no change in the lights but the charging circuit for condenser QJ now extends over contact $C15$ and the switch VEW . Moreover, relay D is de-energized by the opening of contacts $C1$ and owing to the closure of contact $C16$ a circuit is prepared for shunting condenser QJ via relay contact $d2$. If there is no further traffic, relay D will remain deenergized and contact $d2$ will remain open so that the condenser QJ will become fully charged, but until relay E for the $N-S$ road is operated the contact $e2$ will be open and since also cam contact $C6$ is open in this position 3, relay J cannot be operated and condenser QK cannot be charged so that neither relay J nor relay K is operated and the cam shaft remains in position 3 with right of way on the $E-W$ road.

If further vehicles arrive on the EW road however relay D is again operated and shunts the condenser by way of the comparatively low resistance YE and contact $d2$ and thus extends the time which will be required for the condenser to be charged to the striking voltage of the lamp FJ . It may be pointed out that since in these circumstances relay D is only operated while the vehicle is actually passing over the detector pad, the amount of extension obtained is dependent on the speed of the vehicle, being greater for a slow moving vehicle than for a fast moving one.

If now a vehicle should arrive on the road NS , relay E will be operated and contacts $C17$ will complete a circuit for effecting the operation of relay J as soon as condenser QJ is sufficiently charged. Hence, if a break of sufficient length to permit the striking voltage of the neon lamp FJ to be reached occurs in the traffic on the road EW , relay J will be operated and will advance the cam shaft to positions 4, 5 and 6

in turn in the manner previously described but by successively charging condenser QA over adjusting switches LEW and INS to give right of way to the road NS .

In case, however, the traffic on the road EW should be substantially continuous, that is to say, there should be no break in traffic flow sufficiently long to permit condenser QJ to charge up, the maximum timing circuit involving the condenser QK comes into operation. It will be noted that this circuit comes into operation as soon as there is a waiting vehicle on the road NS at which time relay E is operated and locks up over contacts $C18$. The charging circuit for condenser QK now extends over contacts $C12$ and the switch MEW by means of which a resistance is connected in circuit which will permit the condenser QK to charge up only after an interval considerably greater than that required for the charging of condenser QJ .

It is assumed in the present case that the road NS is the main road extending through the various intersections and it will be seen from the fact that cam contacts $C8$ are only opened in position 6 that if there should be a continuous stream of traffic coming from the road EW , that is the side road, the main road will receive right of way as soon as the condenser QK becomes sufficiently charged because relay K which also operates the solenoid S over armature $k1$ has its operating circuit completed over contacts $C8$ in position 3 of the cam shaft. In the case, however, of continuous traffic on the main road, that is NS , with traffic waiting on the side road EW , even though the condenser QK becomes sufficiently charged it is impossible for it to discharge through relay K and neon lamp FK until the instant at which a pulse is received from the master timer to energize the master control relay c' (corresponding to relay C in Fig. 2) and operate armature $c'1$. Accordingly if the traffic on the main road is substantially continuous so that the several individual controllers are working on their maximum periods, the actual instants at which the several controllers withdraw right of way from the main road are controlled by the master controller thru relay C' and contact $c'1$ in each individual controller. Because the time sequence of operation of the several relays C' (C in Fig. 2) is determined by the master timer, as explained in connection with Figs. 1 and 2, the time when each relay C' permits its associated controller to withdraw right of way from the main road thus may be adjusted at successive intersections along a main road to permit main road traffic to proceed with the minimum delay.

It will be noted that armatures $d3$ and $e3$ when operated serve to include resistances YF and YG in their respective amber timing circuits so that when right of way is being forcibly removed thus intercepting a stream of traffic an additional amber period is given to facilitate clearing the crossing. Similar control may be obtained by means of the amber extension switches ENS , EEW .

The switches PNS and PEW are so-called arterial switches and when operated ensure that right of way shall return to the associated street in the absence of traffic thereon. Their effect is to simulate the operation of the pads at a time when the street in question is not receiving right of way by energizing the respective relays E and D in cooperation with cam contacts $C18$ and $C17$

respectively in all positions except 6 and 3 respectively, though they do not produce any extension effect when the street already has right of way unless the respective pads are operated.

The solenoid S is provided with three sets of contact springs of which s1 and s2 serve to shunt condensers QJ and QK by low resistances YJ and YK respectively. Springs s3 are effective in conjunction with armature k2 to ensure that without any further operation of the associated detector right of way shall be returned to the street from which it has been forcibly removed.

It will be understood that the master timer and associated control relays are operated continuously so that relay C' in each individual controller is operated once each cycle. This operation only produces any effect however if the traffic on the main road is so heavy as to run the controllers up to their maximum timing periods.

An embodiment of the invention will now be described in which a right of way controller of the type shown in Figure 3, having detectors in the several lanes of approach to the intersection, and with the modifications which will be disclosed in connection with Figure 4, serves as a key controller. The master timer is associated with the key controller and as in Fig. 1 may comprise a rotary stepping switch or telephone line switch, of construction well known to those familiar with the art. The wiper arms of the switch are advanced step by step by a magnet DSM energized periodically by impulses which in this embodiment of the invention originate from a condenser-flasher tube arrangement, similar in all respects to that shown in Figure 1. As mentioned above, the local dependent controllers, for all intersections of the group except the key intersection which is vehicle actuated, may be of the same form as the controller of Figure 2, in which impulses from the master timer control the time when right of way is accorded to the main traffic lane and the cross 45 lane.

Referring now to Figure 4, there are reproduced herein portions of Figure 3 in which modification or addition is required for the use of such a controller at a key intersection according to the invention the balance of Fig. 3 representing principally the road relays D and E and road contacts DEW and DNS, as well as the signal cams and circuits it will be understood are assumed to be a part of Fig. 4. Further only a portion of the master timer of Fig. 1, including modification, has been reproduced in the left hand portion of Fig. 4. The timing circuits of the key controller are now connected to ground from terminal 56 either over back contacts of a relay G or front contacts of a relay H instead of directly to ground as in Fig. 3. Relay G is energized by the closure of an added pair of cam contacts C23 during the main road vehicle interval (shaft position 6), and this breaks the timing circuit to ground at g1, until relay H is energized. A circuit to energize the relay H is completed by armature r1 when the latter is attracted by relay R which is energized in a certain position or positions of the master timer DST by its wiper 13. Relay H may be locked in during the main street vehicle interval over cam contacts C24. It will be understood that the relay R may be placed with the key controller instead of with the master timer as shown in

Figure 4, if desired, the circuits remaining the same as in Figure 4.

A circuit over armature r2, when relay R is energized, is completed over armature g2, either to timing increase magnet INM, or to timing decrease magnet DEM of a double-acting rotary switch DDT, depending upon whether g2 be engaging contact 30 or contact 31 it will be appreciated that relay R may be located with the key controller if desired, in case the latter is remote from the master timer.

The rotary stepping switch DDT is of a type provided with two stepping mechanisms so connected that the wiper arm 12 may be operated over its contact bank in either direction. For this purpose magnet DEM is arranged to notch in one direction the ratchet wheel 25, Figures 5 and 6, mounted on shaft 26, and magnet INM is similarly fixed to notch ratchet wheel 27, on the shaft 28, in the opposite direction of rotation to shaft 26. The differential gearing permits member 29 to revolve in either direction, depending upon whether shaft 26 or 28 is rotated. Wiper 12 is mounted on member 29 and is suitably shaped to revolve over its associated bank of contacts of the switch DDT either clockwise or counterclockwise.

Again referring to Figure 4, the contacts of switch DDT are connected to points which may preferably be equidistant on rheostat 22, which stands in the condenser QB and flasher tube N impulsive circuit of magnet DSM of the master timer stepping switch DST.

Assume now that the solenoid of the key controller steps its camshaft into shaft position 6, the A phase or main street vehicle interval position. Cam contacts C23 are closed energizing relay G. Thus at armature G1 the direct current feed for the A phase vehicle interval and maximum timing circuits become disconnected from ground, thereby stopping all timing. A particular contact on the bank 4a of the rotary switch DST in the master timer is selected in accordance with the predetermined progressive plan for operating the dependent controllers so that the wiper 13 comes into engagement with this contact at the same time as the cam contacts C23 close, when the master timer and the key controller are operating on the same length cycle.

When the master timer and the key controller, due to traffic conditions affecting the latter, are not operated in the same length cycle and if the master timer is operating on a longer cycle than the key controller, relay R, which is connected to the synchronizing contact of bank 4a, will be energized after relay G, and when relay R has attracted armature r1, relay H is energized and locked in over its armature h1 and cam contacts C24. This pair of contacts is closed only during the phase A vehicle interval, shaft position #6. Relay R at armature r2 completes a circuit over armature g2 to energize decrease magnet DEM of double acting rotary switch DDT. Accordingly magnet DEM causes wiper arm 12 to be stepped clockwise one contact, thereby reducing the amount of resistance 22 in the charging circuit of condenser QB. The frequency of impulses from the impulsive circuit to magnet DSM of the master timer is thus increased and consequently the time for one cycle of the master timer is decreased.

In the circumstances described, since relay R has operated after relay G, when the master timer is operating on a longer cycle, the decrease

magnet DEM, energized, reduces the master timer cycle time by a certain amount, for instance 4%. If however, relay R is operated before relay G, which sequence occurs when the master timer is operating on a shorter length cycle than the key controller, the increase magnet INM is energized, wiper arm 12 is stepped counterclockwise one contact, thereby increasing the resistance 22 in the impulse-generating circuit, and the master cycle time is increased say by 4%. As already explained, relay R upon being energized, pulls in relay H which locks-in at armature h1, and at armature h2 reconnects the direct current feed for the timing circuits to ground, whereupon the key controller recommences normal timing; the condensers QJ and QK begin to charge and upon operation of relay J or K the cam shaft is advanced into position 1. When the cam shaft is stepped into the amber leaving phase A position the cam contacts C23 and C24 open, relays G and H drop out and the key controller and master timer operate thru their next cycle independently.

It will thus be seen that successive energizations of relay G are raced against successive energizations of relay R. If the cycle time of the key controller is longer than that of the master timer, in which case relay R is energized before relay G, the next cycle of the master timer is lengthened; if the cycle of the key controller is shorter than that of the master timer, in which case relay R is energized after relay G, the key controller timing is interrupted until the master timer completes its cycle, and the next cycle of the latter is decreased.

In lieu of the arrangement just described in which the armatures g1 and h1 are inserted in parallel between terminal 56 and ground, it will be obvious to those versed in the art that in an alternative arrangement terminal 55 may be connected to ground and the armatures g1 and h1 placed in parallel between terminals 55 (or ground) and 56. This effect is illustrated by shifting switch TZ to its ground position. Whereupon the relay G, when energized, instead of interrupting all timing breaks all except the charging circuit to condenser QJ. Thus the key controller will advance to its next shaft position, position #1, as soon as relay H is energized, if condenser QJ has reached the flash voltage of tube FJ, or as soon thereafter as the flash voltage is reached.

The armature c'1 of Figure 3 may be replaced in the case of the key controller by an armature r3 in the master timer for example, as shown in Figure 4, or the cam contacts C8 may be shunted altogether, since the arrangement to stop timing in the key controller in position 6 when this controller completes its cycle before the master timer holds the two machines closely in step, and renders other coordinating means unnecessary.

It will be appreciated that dependent local controllers of the type shown in Figure 2 and operated from the master timer according to the method shown in Figure 1 and thereinafter described may be replaced by full vehicle actuated right of way controllers of the type shown in Figure 3, or they may be replaced by controllers having vehicle detectors in the side roads only with the vehicle detectors circuit on the main road via DNS preferably permanently closed. In the latter case a system of control from the master timer becomes established in which impulses from the master timer are sent over control leads to relay C' in the dependent

controller in the same fashion as to relay C in Fig. 1 and Fig. 2, and such impulses from the master timer will indicate when right of way may be removed from the main road if the side road detector has been operated. The master timer would in this case however be set to give the impulse to relay C' at the point in its cycle at which it is desired to have transfer of right of way from the main road NS to the side road EW occur at the local controller.

In addition if desired a second impulse operating a relay B', in similar fashion to relay B in Fig. 1 and Fig. 2 for example, may indicate when right of way must return to the main road, if right of way has been retained on the side road by continuous traffic. Fig. 7 shows how Fig. 3 may be modified in accordance with the arrangements of Fig. 1 and Fig. 2 to provide two such control impulses per cycle of the master timer, the armature c'1 cooperating with cam contact C'8 in position 6 to control transfer of right of way from NS and armature b'1 cooperating with cam contact B'19 in position 3 to control transfer of right of way from EW by the master timing circuit. With these alternative arrangements if there is no traffic on the side road, right of way will remain continuously on the main road. Also right of way will return to the main road after being accorded to the side road if all the side road traffic has passed so that condenser QJ is charged and tube FJ operates before the second impulse is received.

Thus the several objects specifically brought out above, and others are achieved. It is to be understood that various modifications in the structural details or arrangements of the parts, or changes in the designs herein exemplified may be made without departing from the spirit of the invention as defined by the claims.

Having described my invention what I claim as new and desire to secure by Letters Patent of the United States is:

1. In a traffic control system for a plurality of intersections of interfering traffic lanes, the combination of means for according right of way through a cycle to the several lanes at one intersection, a second means at another intersection and adapted to be actuated by traffic for according right of way through a cycle to the several lanes at the latter intersection variable in accordance with traffic actuations in said several lanes, means for increasing the cycle of the first means, means for decreasing the cycle of the first means, and selective means responsive to the order of completion of the cycles of the first and second means for selecting between said means for increasing or decreasing the cycle of said first cycle increasing and cycle decreasing means.

2. In a traffic signal control system for a plurality of intersections of interfering traffic lanes, the combination of right of way signals at the several intersections, a primary right of way signal controller at one intersection and traffic actuatable devices in the lanes thereat, said controller operable in response to actuation of said traffic actuatable devices in the respective lanes at said one intersection to accord right of way cyclically to the several lanes thereat in succession for variable periods of time in accordance with said actuations, a secondary controller for controlling the signals at another intersection through a cycle of right of way indications, means for altering the length of the cycle of said secondary controller, means operable responsive

to the order of completion of the cycles of the primary and secondary controllers for operating said first named means.

3. In a traffic signal control system for a plurality of intersections the combination of right of way signal indicators at each intersection, a primary signal controller at one intersection and traffic actuatable devices in the lanes thereat, said controller operable in response to actuation of said traffic actuatable devices in the respective lanes at said one intersection for according right of way cyclically to the several lanes thereat in succession for variable periods in accordance with said actuations, a secondary signal controller for operating the signals at another intersection through a cycle of right of way indications, means for lengthening and means for shortening the cycle of the secondary controller, and selective means responsive to the order of completion of the cycles of the primary and secondary controllers to operate either said lengthening or shortening means toward balancing the length of said controller cycles.

4. In a traffic control system for a plurality of intersections of interfering traffic lanes, the combination of right of way signals displayable at the several intersections, a key right of way controller at one of the intersections and traffic actuatable devices in the lanes thereat, said controller operable in response to actuation of said devices in the several lanes at said one intersection for according right of way cyclically to the several lanes in succession for variable periods in accordance with said actuations, a master timer for cyclically controlling the display of such signals to the several lanes at a second of said intersections, means associated with said master timer for altering the length of the next cycle of the master timer to approach the duration of the last completed cycle of the said key controller, and further means operating when the master timer has reached the end of its cycle for making said first means operable for such next cycle.

5. In a traffic control system for a plurality of intersections of interfering traffic lanes, the combination of right of way signals displayable at the several intersections, a key right of way controller at one of the intersections and traffic actuatable devices in the lanes thereat, said controller operable in response to actuation of said devices in the several lanes at said one intersection for according right of way cyclically to the several lanes in succession for variable periods in accordance with said actuations, a master timer for cyclically controlling the display of such signals to the several lanes at a second of said intersections, means associated with said master timer for altering the length of the next cycle of the master timer to approach the duration of the last completed cycle of the said key controller, and further means operating when the key controller completes its cycle before the master timer completes its cycle for stopping said controller at the end of the cycle of the right of way controller until the master timer has completed its cycle.

6. In a traffic control system for a plurality of intersections of interfering traffic lanes, the combination of right of way signals at the several intersections, a cyclic master timer comprising a periodic electrical impulse generator and a switching mechanism which is stepped thru a cycle in steps by and corresponding to said impulses for operating said signals at one of said 75 intersections thru a cycle of right of way indi-

cations, a key controller at another intersection and traffic actuatable devices located in the several lanes thereat, said controller operable in response to actuation of said devices in the respective lanes at said latter intersection for successively according right of way cyclically thru said signals to the several lanes for variable periods in accordance with said actuations, means associated with the master timer for altering the length of its cycle toward the length of the cycle of said 10 key controller, and means operating at the end of each cycle of the master timer for operating said first means.

7. In a traffic control system for a plurality of intersections of interfering traffic lanes, the combination of a cyclic master timer comprising a condenser, means for producing a charge on said condenser varying over a time period to a certain value, means including a flasher tube connected to said condenser and operable only 20 when the charge on said condenser reaches said certain value to generate an impulse, and a cyclic switching device which is stepped thru its cycle in steps by and corresponding to said impulses, right of way signals at one of the intersections 25 and controlled cyclically by said master timer, a right of way controller at another intersection and traffic actuatable devices located at the several lanes thereat, said controller being operable in response to actuation of said devices at 30 said latter intersection for successively according right of way cyclically to the several lanes for variable periods in accordance with said actuations, a variable resistance in said charge varying means for altering the frequency of said impulses to the master timer by varying the time rate of variation of charge of the condenser, and means for automatically varying said resistance for altering the cycle length of the master timer toward the length of the cycle of said right of way 40 controller, in accordance with the order of completion of the cycles of said master timer and said controller.

8. In a traffic control system for a plurality of intersections of interfering traffic lanes, the combination of right of way signals at each intersection, a key controller and traffic actuatable devices in the lanes at one intersection and connected to said controller for controlling the signals thereat, said controller being operable in response to actuation of said traffic actuatable devices at one intersection for according right of way to the several lanes in succession in a cycle for variable periods in accordance with the said actuations, a master timer for operating the signals at another intersection through a cycle of right of way indications, means associated with the master timer for increasing its cycle and means operable upon the master timer reaching the end of its cycle before the key controller has completed its cycle 60 to make said first means operable.

9. In a traffic control system for a plurality of intersections of interfering traffic lanes, the combination of right of way signals at each intersection, a key controller and traffic actuatable devices in the lanes at one intersection and connected to said controller for controlling the signals thereat, said controller being operable in response to actuation of said traffic actuatable devices at one intersection for according right of way to 70 the several lanes in succession in a cycle for variable periods in accordance with the said actuations, a master timer for operating the signals at another intersection through a cycle of right of way indications, means associated with the 75

- master timer for decreasing its cycle and means operable upon the master timer reaching the end of its cycle after the key controller has completed its cycle to make said first means operative.
- 5 10. In a traffic control system for a plurality of intersections of interfering traffic lanes, the combination of right of way signals at each intersection, a key controller and traffic actuatable devices in the lanes at one intersection and connected to said controller for controlling the signals thereat, said controller being operable in response to actuation of said traffic actuatable devices at said one intersection for according right of way to the several lanes in succession in a cycle 10 for variable periods in accordance with the said actuations, a master timer for operating the signals at another intersection through a cycle of right of way indications, means associated with the master timer for decreasing its cycle, and means operable upon the key controller completing its cycle before the master timer to stop said key controller until the master timer has completed its cycle, whereupon said first means is rendered operative.
- 20 11. In a traffic control system for a plurality of intersections of interfering traffic lanes, the combination of right of way signals at each intersection, a key controller and traffic actuatable devices in the lanes at one intersection and connected to said controller for controlling the signals thereat, said controller being operable in response to actuation of said traffic actuatable devices at said one intersection for according right of way to the several lanes in succession in a cycle 25 for variable periods in accordance with the said actuations, a master timer for operating the signals at another intersection through a cycle of right of way indications, means including a circuit and operable when said circuit is completed to shorten the cycle of said master timer, means operable upon the key controller completing its cycle before the master timer has completed its cycle for stopping said key controller and for preparing said circuit to shorten the next succeeding cycle of said master timer, and means operable when the master timer thereafter completes its cycle for restarting said key controller and for completing the circuit prepared by said first means.
- 30 12. A traffic control system for a plurality of intersections of interfering traffic lanes including in combination an electrical periodic impulse generator, a cyclic rotary electric switching device which is stepped through its cycle in steps by and corresponding to said impulses, right of way controlling means at one intersection and controlled by said rotary switching device, a key right of way controller and traffic actuatable devices in the lanes at another intersection and connected to said controller, said controller being operable responsive to actuation of said traffic actuatable devices at said latter intersection for according right of way to the several lanes in succession in a cycle for variable periods of time in accordance with said actuations, means associated with said impulse generator for increasing the frequency of its stepping impulses and means co-operable upon the said rotary switching device completing its cycle after the key controller has completed its cycle to make said first means operative.
- 35 13. A traffic control system for a plurality of intersections of interfering traffic lanes including in combination an electrical periodic impulse generator, a cyclic rotary electric switching device

which is stepped through its cycle in steps by and corresponding to said impulses, right of way controlling means at one intersection and controlled by said rotary switching device, a key right of way controller and traffic actuatable devices in the lanes at another intersection and connected to said controller, said controller being operable responsive to actuation of said traffic actuatable devices at said latter intersection for according right of way to the several lanes in succession in a cycle for variable periods of time in accordance with said actuations, means associated with the said impulse generator for decreasing the frequency of its stepping impulses and means co-operable upon the said rotary switching device completing its cycle before the key controller has completed its cycle to make said first means operative.

14. A traffic control system for a series of intersections of cross traffic lanes with a common 20 main lane including, in combination, right of way signals at each intersection, an electrical periodic impulse generator, a rotary electric switching device which is operated by said impulses to control said signals through a cycle of right of way indications with a progressive time phase displacement of such indications at successive intersections, a key right of way controller and traffic actuatable devices in the lanes at one intersection and connected to said controller, said controller being operable responsive to actuation of said traffic actuatable devices at said latter intersection, for according right of way to the several lanes in succession in a cycle for variable periods of time in accordance with said actuations, means associated with said impulse generator for altering the frequency of stepping impulses to the switching device to lengthen or shorten its cycle to approach the duration of the last completed cycle of said right of way controller, and further means 40 operable when the said switching device has completed a cycle for making said first means effective.

15. A traffic control system for a series of intersections of cross traffic lanes with a common 45 main lane, including, in combination, right of way controllers at each intersection, a key right of way controller and traffic actuatable devices in the lanes at one intersection and connected to said controller, said controller being operable in response to actuation of traffic actuatable devices in the approaches to said intersection for according right of way to the several lanes in succession in a cycle for variable periods of time in accordance with said actuations, a master timer comprising an electrical periodic impulse generator and a rotary electric switching device operated cyclically by said impulse for operating the indications of the other controllers with a progressive time phase displacement at successive 60 intersections, means including a resistance for regulating the time spacing of said impulses, means for altering said resistance to lengthen or shorten the cycle of the master timer toward the length of the cycle of said key right of way controller, and further means operable when the said switching device has completed a cycle to make said first means active.

16. A traffic signal control system for a series of intersections of cross traffic lanes with a 70 common main lane including, in combination, a key right of way controller, traffic actuatable devices in the lanes at one intersection and connected to said controller, said controller being operable in response to actuation of said traffic actuatable devices.

atable devices at said one intersection for according right of way to the several lanes in succession in a cycle for variable periods in accordance with said actuations, a right of way controller and a traffic actuatable device in the cross lane at another intersection and connected to said latter controller, said controller operable in response to actuation of said traffic actuatable device in the cross lane to accord right of way to such cross lane, a cyclic master timer for controlling the ability of said latter controller to respond to actuation of its associated actuatable device to maintain the accord of right of way at the intersections in predetermined time relation, and means for altering the length of the cycle of said timer in accordance with the length of the cycle of said key controller, and means functioning when the master timer has completed a cycle for making said first means operable.

17. In a traffic control system for two intersections of interfering traffic lanes including, in combination, right of way signals at each intersection, mechanism for controlling the signals at one intersection comprising a condenser, means for producing a charge on said condenser varying over a time period to a certain value, means including a flasher tube operable only when said charge on said condenser reaches said certain value for generating a momentary impulse, and a rotary switching device which is stepped thru a cycle in steps by and corresponding to said impulses for operating said signals thru a cycle of signal indications; a key controller at the other intersection for controlling the right of way signals to the several lanes thereof, and traffic actuatable devices in the last said lanes and connected to said controller, said controller being operable in response to actuation of said traffic actuatable devices at said latter intersection for according

right of way thru said signals to the several lanes in succession in a cycle for variable periods of time in accordance with actuations; a variable resistance in said charge varying means for adjusting the time rate of variation of charge, and control means for increasing said resistance when said switching device completes its cycle before said key controller. 5

18. In a traffic control system for two intersections of interfering traffic lanes including, in combination, right of way signals at each intersection, mechanism for controlling the signals at one intersection comprising a condenser, means for producing a charge on said condenser varying over a time period to a certain value, means including a flasher tube operable only when said charge on said condenser reaches said certain value for generating a momentary impulse, and a rotary switching device which is stepped thru a cycle in steps by and corresponding to said impulses for operating said signals thru a cycle of signal indications; a key controller at the other intersection for controlling the right of way signals to the several lanes thereof, and traffic actuatable devices in the last said lanes and connected to said controller, said controller being operable in response to actuation of said traffic actuatable devices at said latter intersection for according right of way thru said signals to the several lanes in succession in a cycle for variable periods of time in accordance with actuations; a variable resistance in said charge varying means for adjusting the time rate of variation of charge, control means for decreasing said resistance when said switching device completes its cycle after said key controller, and further means operable upon said switching device so completing its cycle to make said control means operate. 15 20 25 30 35
